(57) **CLAIM**

The ornamental design for a car module, as shown and described.

DESCRIPTION

FIG. 1 is a top perspective view of the car module;
FIG. 2 is a left view of the car module;
FIG. 3 is a rear view of the car module;
FIG. 4 is a front view of the car module;
FIG. 5 is a top view of the car module;
FIG. 6 is a bottom view of the car module;
FIG. 7 is a right view of the car module;
FIG. 8 is a top perspective view of a second embodiment of the car module;
FIG. 9 is a left view of the second embodiment of the car module;
FIG. 10 is a rear view of the second embodiment of the car module;
FIG. 11 is a front view of the second embodiment of the car module;
FIG. 12 is a top view of the second embodiment of the car module;
FIG. 13 is a bottom view of the second embodiment of the car module; and,
FIG. 14 is a right view of the second embodiment of the car module.

The elements and/or structures shown in broken lines are shown for illustration purposes only and do not form part of the claimed design.
